AUTO BODY HEATER

Claude H. F. Whitlark and Frederick A. Welie,
Jr., Detroit, Mich., assignors to McAleer Manufacturing Company, Detroit, Mich., a corporation of Michigan

Application August 6, 1936, Serial No. 94,588

4 Claims. (Cl. 257—137)

This invention relates to heaters and in particular relates to a circular radiator heater for heating the interior of automobile bodies.

Objects of the invention are to provide an auto body heater construction having the parts thereof so constructed and arranged that the fan and motor are readily accessible and removable from the heater; to provide a heater construction in which a core is formed of a plurality of flat tubular members having fins on their surfaces of such a construction that the maximum efficiency in heat transfer is obtained; to provide a heater materially shortened in construction so that it will require a minimum of space within the automobile body; to provide the deflecting and baffling means of such a character that the direction and volume of the heated air entering the body may be effectively controlled; to provide a fan motor mounting of such a construction that the motor may be maintained in a cool condition during operation; and to provide a heater construction which is simple to manufacture and efficient in use.

Other objects of the invention will become apparent from the following specification, the drawings relating thereto and from the claims hereinafter set forth.

In the drawings in which like numerals are used to designate like parts in the several views throughout;

Fig. 1 is a front elevational view with parts broken away of an auto body heater embodying features of the present invention;

Fig. 2 is a cross-sectional view with parts in elevation taken substantially along the line 2—2 of Fig. 1;

Fig. 3 is an enlarged fragmentary cross-sectional view taken substantially along the line 3—3 of Fig. 1;

Fig. 4 is an enlarged fragmentary cross-sectional and elevational view taken substantially along the line 4—4 of Fig. 2;

Fig. 5 is an enlarged fragmentary cross-sectional view taken substantially along the line 5—5 of Fig. 4; and,

Fig. 6 is a vertical cross-sectional view showing a modified structure for mounting the motor within the core.

It is, of course, recognized that auto body heater radiators are old and the present invention relates to an improvement over the known types of auto body heaters. One of the difficulties with the prior types of heaters is that the air passing through the heater is not heated to a sufficient extent and the heaters are therefore

not as efficient as is desired. In order to obtain a maximum efficiency in heat transfer in heating the air passing through the heater, the present invention contemplates the construction of a heater in which a core is provided, including upper and lower headers connected by substantially flattened semi-circular tubes spaced at intervals along the length of the headers. A suitable heating medium, as hot water, or steam, is supplied to one of the headers, circulates through the tubes to the other header, and away from this last header. The core is substantially circular in cross section, and the elongated flat portions of the tubes are directed radially inwardly so that air entering the heater passes over a maximum area to provide greater efficiency in heating the air. Also, in order to insure maximum heating of the entering air, radiating fins are provided on the radially directed surfaces of the semi-circular tubes between adjacent tubes. The particular shape and construction of these fins form an important feature of the present invention; and the fins are constructed from an elongated strip of heat conducting metal, such as copper, for example, by passing the strip between spaced gears of such a configuration that trench-like zigzag grooves are provided transversely of the strip of a depth substantially equal to the distance between adjacent tubes. The air passing into the heater travels radially of the core and as it is confined to the zigzag grooves, these grooves will prevent direct straight line entrance into the heater thereby causing turbulence in the incoming air and efficiently heating the air.

A motor and fan are provided in the core to draw air radially therethrough and discharge it through the forwardly facing opening through a louver plate removably mounted over the opening, and provided with doors or baffles forwardly of the louver plate and pivotally mounted to the louver plate. The louvers of the plate and the baffle doors are so constructed that the discharge of heated air may be effectively controlled as to direction and volume to satisfy the requirements of occupants of the vehicle.

Another difficulty with prior types of heaters is that it is difficult to conveniently remove the fan and motor from the heater construction, particularly in that heretofore the entire heater requires removal from the automobile to permit removal of the motor, and in the present invention the motor and fan are mounted relative to the core so that simply by removing the front plate and the shroud and the louver plate as a unit, and the convenient removal of several sup-

porting screws for the motor, without disturbing the mounting of the heater itself in the automobile, the motor and fan may be conveniently removed through the face of the heater. Also the present invention contemplates the provision of openings through the motor casing and motor mounting means communicating with the relatively cool outside air for ventilating the motor where such ventilation is desired.

For a better understanding of the invention reference may be had to the drawings in which an auto body heater generally designated at 10 is mounted upon a supporting member 12, preferably the dash board of the vehicle. The heater structure comprises a base plate 14, preferably formed of a sheet metal stamping, substantially circular in shape and having a peripheral flange 16. The base plate 14 is provided with diametrically opposed openings 18 adjacent the outer periphery which have threaded bushings 20 extending therethrough. Upper and lower headers 22 and 24 respectively are provided, and as they are substantially identical only one need be described for an understanding of both. The header 22 is preferably constructed of the split type having a male half 24 and a female half 26 which are preferably push fitted together and are of such a shape that when the two halves are in assembled position the header has substantially flat elongated side portions 28 within which transversely extending elongated slots 30 are spaced longitudinally of the header. The header 22 is enclosed at its forward end and has a reduced substantially circular opening with an outwardly directed annular flange 32 adjacent its rear end over which a header tube 34 is connected in communication with the interior of the header. The header tube 34 fits within the bushing 20 which in turn fits through an opening in the dash. The heater is thus held in place on the dash by means of nuts 35, or the like, which may be threaded over the bushing 20.

Substantially semi-circular flattened cross tubes 36 communicate with the interior of the headers through the slots 30 and thus communicate the upper and lower headers with each other, and with the headers form a substantially circular core for the heater. The tubes 36 are elongated in one transverse direction through the tubes so that they have flattened side portions 38 directed radially inwardly of the heater. Radiating fins 40 are secured to one of the substantially flat portions 38 of each tube and are located in assembled position between adjacent tubes.

The radiating fins 40 are formed from a sheet metal strip of a material with good heat conducting characteristics, preferably copper, by passing the strips through spaced gears of such construction that the strip is shaped to provide transversely extending zigzag grooves 42. The grooves 42 are trench-like and zigzag in character, and the grooves 42 may be considered as being divided into a plurality of portions or sections 44, 46 and 48 transversely of the strip so that all of the sections lying in one plane longitudinally of the strip are parallel to each other, as for example all of the sections 44 are parallel to each other, while adjacent sections, such as 44 and 46, are angularly disposed relative to each other so that a direct straight line path through the groove is avoided.

The grooves 42 have a depth substantially the same as the distance between the tubular element 36 and have a transverse width substantially the same as the straight or flat portions

38 of the tubes 36. The strip 40 is cut into lengths substantially the length of the semi-circular tubes 36 and are then bent to substantially the curvature of the tubes 36 and secured in heat transfer relation to one of the flat portions 38 of each of the tubular members 36, as by soldering, or a similar manner.

As is evidenced from the above description relative to the drawings, when in assembled position the radiating fins 40 provide generally radially directed passages into the interior of the core. The zigzag character of the passages 42 prevents direct entrance of air into the interior of the core and causes turbulence of the entering air, thereby obtaining maximum heat- 15

A motor 50 having a fan 52 thereon is mounted within the core substantially central of the core and base plate 14, and is secured to the plate 14 by means of a mounting or supporting 20 plate 54 which is substantially circular in shape and to which the motor is removable mounted by means of nuts and bolts 56, or the like. The mounting or supporting plate 54 extends outwardly beyond the outer periphery of the casing 25 of the motor 50, and is there provided with openings 58 adjacent the outer periphery of the plate 54 at spaced intervals therearound. The openings 58 are aligned with openings in the base plate 14 and suitable means such as screws 60 are 30 provided for removably securing the supporting plate 54 to the base plate 14.

A substantially circular shroud 62 having a central opening 64 is removably mounted at the forward edge of the core formed by the headers 35 22 and the foremost tube 36 and radiating fin 40, the shroud 62 being centrally axially inwardly offset so that the opening 64 is positioned materially to the rear of the foremost tube 36 and slightly to the rear and in surrounding relation 40 to the fan 52. This materially shortens the heater in length so that it requires a minimum of space within the automobile body, and also confines the discharged air to the opening 64.

A louver plate or ring 66, preferably formed of 45 a sheet metal stamping, is substantially circular in shape and has a radially outwardly directed annular flange 68 which is adapted to seat against and be removably secured, in a suitable manner, to the shroud 62. The face of the plate 66 is 50 provided with louvers 70 which extend transversely of the face of the plate 66 and are bent inwardly with their faces directed downwardly so that air impinging thereagainst is directed downwardly.

A pair of doors or baffles 71 and 72 substantially semicircular in shape are pivotally mounted to the louver plate 66 so that each baffle or door may be pivoted about two separate vertical axes. The mounting means for each of the doors comprises 60 a U-shaped hinge support 73 fixedly secured to the inner face of the louver plate 66 by means of rivets, or the like. A hinge 74 with spaced substantially parallel sides 76 is pivotally secured to the hinge support 73 about a substantially vertical axis by means of rivets 78, or the like. The inner end of the side 76 of the hinge is pivotally attached to one of the doors 71 or 72 by means of rearwardly projecting lugs 80 on the doors which have openings therethrough cooperating with openings in the hinge 74 and held in place relative thereto by means of rivets 82, or the like, so that the doors or baffles may be movable about the vertical pivot pins or rivets 82.

It is evident from the above that a construc- 75

tion is provided for directing the air from the heater so that as the air passes through the louvers it is directed downwardly, and by pivotally mounting the doors or baffles so that each one is pivotally mounted about two separate axis, the volume and direction of the air leaving the heater may be varied in a great many different manners. For example, each of the doors may be pivoted about their axis so that they may be pulled away from the face of the heater with the doors lying in substantially the same plane, or they may be so pivoted that the air may be directed by either of the baffles to either side of the heater.

A front cover 91 substantially circular in shape and having a central opening 92 is provided over the front of the core, the central opening 92 being in alignment with the doors 11 and 12 and having an inwardly directed annular flange 93 which bears against the louver plate 68. The outer peripheral edge of the cover 91 is flanged as at 94 to fit over the outer periphery of the shroud 62 in snug engagement therewith and core assembly. The cover 91 is removably held in place on the core by means of spring strips 95 which have inwardly curved rear edges which fit within depressions in the flange 16 of the back plate 14 and have front tongues 96 which fit within slots in the front cover 91.

In the structure shown in Fig. 6 a modified mounting for the motor within the core is provided in which the motor 50 is enclosed within a shroud or casing 86 which is suitably secured to the front face of the motor and extends rearwardly so that the rear edge is in annular contact with the motor mounting or supporting plate 54. Openings 87, 88, 89, and 90 are provided in the base plate 14, the motor mounting or supporting plate 54 and in the casing of the motor 50, so that relatively cool outside air may be drawn through the motor by the low pressure area created by the fan to cool the motor and keep it in proper operating condition. This is particularly important in structures such as the present one in which the motor is mounted within the core of the heater and subjected to the heat from the heating radiator.

Formal changes may be made in the specific embodiments of the invention described without departing from the spirit and substance of the

invention, the scope of which is commensurate with the appended claims.

What we claim is:

1. In a heater having an open face, a louver plate over said open face, said louver plate having transversely extending, downwardly directed louvers, baffles forward of said louver plate for closing said open face, and elongated mounting means one end of which is pivotally attached to each of said baffles and the other end of which is pivotally attached to said louver plate. 5

2. In a heater having an open face, a louver plate over said open face, the louvers being arranged to direct air passing therethrough downwardly, baffle plates forward of said louver plate 15 for closing said open face, and elongated mounting means one end of which is attached to said baffles for pivotal movement of said baffles about axes at an angle to said louvers and the other end of which is attached to said louver plate for 20 pivotal movement with respect to said louver plate.

3. In a heater having a substantially round core and an open face in which a fan and motor are mounted within said core, a louver plate over 25 said open face, said louver plate having transversely extending downwardly directed louvers, baffles forward of said louver plate for closing said open face, and elongated mounting means one end of which is pivotally attached to each of 30 said baffles and the other end of which is pivotally attached to said louver plate.

4. In a heater having a substantially circular core with a forwardly facing opening and in which a fan and motor are mounted within said core, a shroud mounted on the front of said core having a portion extending rearwardly in surrounding relation to said fan to provide a confining discharge opening for the heated air, a louver plate over said opening secured to said 40 shroud, baffle plates forward of said louver plate for closing said opening, mounting means pivotally attaching said baffle plates to said louver plate, said shroud, louver plate and baffles forming a removable unit, and means removably 45 mounting said shroud, louver plate and baffles as unit on said core.

CLAUDE H. F. WHITLARK.
